UNITED STATES PATENT OFFICE

EDWIN E. BARNEY, OF NEW ROCHELLE, NEW YORK, ASSIGNOR TO REMINGTON TYPEWRITER COMPANY, OF ILION, NEW YORK, A CORPORATION OF NEW YORK

TYPEWRITING MACHINE

Application filed April 13, 1927. Serial No. 183,466.

My invention relates to multiple-billing mechanism for typewriting machines, and has for its general object the provision of a new and improved machine for handling 5 multiform billing sheets of the character disclosed in the patent to E. Z. Lewis, No. 932,713, dated Aug. 31, 1909, which sheets, interleaved with a reproducing medium, are wound on the platen of the machine, one 10 complete wind or wrap being allotted to each separate form on the sheet, so that the number of forms to be printed at a single operation corresponds with the number of times the sheet is wound or wrapped on the platen. 15 The carrying out of my invention in practicable form has resulted in various detail improvements relating to the feed and control of the multiform work sheet or form sheet itself, the supplying, feeding and control of the reproducing medium or carbon sheet, and various safety devices for insuring the proper cooperation of inter-related parts, all as will hereinafter appear.

To the above ends my present invention 20 consists in the features of construction, combinations of devices and arrangement of parts hereinafter described and particularly pointed out in the appended claims.

The principle of my invention will be 25 found adapted to various styles of writing machines, but the preferred form of the invention, as illustrated in the accompanying drawings, has been applied to a No. 20 Remington typewriting machine.

30 In the drawings:

Fig. 1 is a front elevation on a reduced scale of a Remington typewriting machine embodying my invention, the upper part of the frame or supporting stand on which the 35 machine is mounted also being shown.

Fig. 2 is a full-sized side elevation of the carriage of the machine with my invention applied thereto.

Fig. 3 is a fragmentary vertical sectional 40 view taken on planes indicated by the section line 3—3 in Fig. 2.

Fig. 4 is a fragmentary, vertical, sectional view taken on planes indicated by the section line 4—4 in Fig. 2.

50 Fig. 5 is a vertical front-to-rear sectional

view taken on a plane indicated by the section line 5—5 in Fig. 1, but drawn to a somewhat larger scale.

Fig. 6 is a fragmentary front-to-rear vertical sectional view taken on a plane indicated by the section line 6—6 in Fig. 1, but drawn to a larger scale. 55

Fig. 7 is a fragmentary front-to-rear vertical sectional view taken on a plane indicated by the section line 7—7 in Fig. 1 but drawn to a larger scale. 60

Fig. 8 is a fragmentary operating view on a plane corresponding with that indicated by the section line 8—8 in Fig. 1, but parts being shown in different positions from the normal 65 position of Fig. 1.

At all section lines arrows indicate the direction in which the view is taken.

While this case has been divided, and some of the claims originally presented herein are 70 now included in two divisional cases, it is deemed necessary to describe the machine as a whole in order that a proper understanding of the features claimed herein may be arrived at. 75

The divisional cases referred to are as follows:

Serial #285,884, filed June 16, 1928;

Serial #293,435, filed July 17, 1928.

Various features which are claimed in said 80 divisional cases will be hereinafter pointed out.

Referring first generally to the embodiment of the invention herein disclosed, there is mounted on standards projecting upward 85 from the stand on which the machine is supported, a magazine or box adapted to contain a supply of multiple-form sheets or work sheets. In the present instance each one of these separate sheets contains six printed 90 forms or blanks, the sheets being folded transversely between each two of the forms. The forms are adapted to be withdrawn from the magazine by hand, one by one, and introduced into the machine over a table or guide plate 95 to a platen-carried clamp which at this time is at the front side of the platen, so that they may be front-fed thereover. Normally lying between the open clamp and the face of the platen is the free end of a reproducing sheet 100

or carbon strip which is supplied from a carbon carrying roll which is connected by gearing to special platen turning mechanism operative by a handle. Said handle is connected by gearing to the platen and is effective when actuated to close the clamp, thereby clamping the bottom edge of the bill sheet and through it the carbon paper to the platen and thereafter to turn the platen continuously in backward direction through a plurality of complete revolutions, thus winding thereon the bill sheet and the carbon sheet in interleaved relationship so that the type imprints will be reproduced on all of the bill forms at a single printing operation. As soon as the bill is completely wound in place, paper feeding devices are thrown into cooperative relationship with the platen in order to feed the bill from line to line and also to promote the proper ejection of the bill when the platen receives a continuous forward bill ejecting movement, these feeding devices being ineffective during the winding on of the bill which is brought about entirely through the holding action of the clamp on the platen. On completing one line of writing, the platen may be line-spaced so as to advance the writing to the next line and so on until the forms are completely written. Thereafter the handle is actuated to continuously rotate the platen forward and eject the multiform bill sheet, the carbon at the same time being rewound on its holder. The operation above outlined is repeated for each multiple bill sheet.

It has been found in practice that the chief problem in controlling multiple bill sheets of the type herein used, together with a reproducing sheet, arises from the difficulty of obtaining accurate, smooth and uninterrupted feeding, and retraction of the sheets. I have provided various means for insuring such feeding and retraction, some of which may be briefly referred to at this point as follows: Means are provided for preventing the actuation of the bill mechanism mounted on the carriage of the typewriting machine unless it is in exact register or proper relationship with the magazine or supply holder which is mounted on the stand or stationary frame. The clamp on the platen is caused to close with a snap so as promptly to grip the ends of the bill sheet and carbon sheet before the rotation of the platen is begun. In order to compensate for the variation of diameter between the carbon supply roll holder as the carbon paper winds off it, and the platen, as the bill sheet and carbon paper wind on it, and vice versa, a spring connection or take-up is provided in the gear connection between the carbon roll holder and the actuating handle. The line space detent is automatically thrown out of the line spacing ratchet wheel at the beginning of the continuous backward rotation of the plat-

en, and is automatically restored to operative position when the bill sheet has been completely wound into place on the platen. Thereafter the line space detent remains effective until the line spacing of the bill is completed and the handle is actuated to eject the written bills, when the detent is again automatically thrown out so that during the ejecting operation, the detent is ineffective, thus permitting a free ejecting movement of the platen. Positive paper feeding means are provided to assist the ejection or winding off of the bill, coupled with devices for preventing such feeding means from interfering with the winding on of the bill under the pull of the paper clamp. Means are provided for preventing the operation of the multiple bill mechanism unless a work sheet is clamped in place for winding on.

All of these means and devices cooperate to insure the proper operation of the mechanism and to produce a smooth accurate control of the bill and carbon sheets with a minimum of effort and also with the practical elimination of the danger of "spiraling" or inaccurate feeding, which is fatal in this style of work. Other features of the construction will be referred to in the following detailed description.

As shown in Fig. 1 the magazine or holder 1 which is preferably made of sheet metal, is provided with cut-outs, and is in what may be termed skeleton form for the sake of lightness. The magazine has a top cover 2 hinged at 3 at the rear and has a front wall consisting of two plates 4 between which is left a vertical central opening through which the operator may grasp the forms one at a time and withdraw them from the top of the magazine, the loosely hinged cover yielding or being lifted for the purpose. The upright side portions 5 are formed with vertical guide slots 5^a which receive the end portions of a metal bar 6 which serves as a weight to rest on the pile or stack of folded multiple bill forms 7 within the magazine.

It will be understood that the rod may yield or move upward in its guide slots whenever a bill sheet 7 is withdrawn from the magazine. Knobs or blocks 8, secured to the projecting end portions of the rod 6, prevent its accidental withdrawal. The bottom of the magazine has secured to it near its ends a pair of clamping blocks 9 which are secured by screws 10 to a cross bar 11. This provides for a bodily tilting adjustment of the magazine as well as an adjustment of it along the supporting rod 11. Said rod is mounted in clamping blocks 12 held in their position of vertical adjustment by clamping screws 13 to a pair of uprights or standards 14 that rise from the rear portion of a frame or stand 15 on which the typewriting machine is supported. This stand may be of ordinary construction but the uprights 14 have been added

thereto to provide a support for the magazine. It will be observed that the mounting is such that the magazine is adjustable sidewise, may be given a tilting adjustment around the bar 11 and receive a bodily up-and-down adjustment on the uprights 14. The frame or stand 15 is provided with cross rods of which the forward one 16 is shown, said cross rod being provided with sockets 17 to receive the feet 18 of the typewriting machine. The main frame of said machine comprises a base portion 19 from which rise posts 20 supporting a top plate 21. Rising from the top plate, as shown in Figs. 1, 2 and 5, are front and rear lugs 22 and 23 to which are screwed stationary guide rails or track ways 24 and 25. These track ways are oppositely grooved and receive antifriction rollers 26 which also cooperate with the front and rear bars 27 and 28 of a carriage truck which further comprises right and left-hand side-bars numbered respectively 29 and 30. A bracket arm 31 secured to the top of the truck at its right-hand rear corner is connected by a band or strap 31^a with the usual carriage motor or spring drum 32 whereby the traveling carriage, comprising the truck 27—30 together with the various parts mounted thereon, is constantly urged leftward along the trackways 24 and 25. The parts of the typewriting machine thus far described are common to the No. 20 Remington typewriter.

In carrying out my invention I provide a new style or construction of platen carried 35 paper clamp; also a new style of paper-table or support; a carbon roll holder; work sheet ejecting means and other devices and parts for controlling these elements, all mounted on the truck or carriage. To provide mountings for these parts, supplementary end plates are mounted on the carriage truck. The right and left-hand end plates numbered respectively 33 and 34 are secured respectively to the outer face of the end bars 29 and 30 by 40 means of screws and dowel pins 35 (Figs. 1, 2 and 3). The platen, indicated as a whole by the reference numeral 36, is in the form of a hollow shell or tube preferably made of aluminum. Said platen, as best shown in 45 Figs. 3 and 5, comprises a tubular body portion 37 to which are secured heads or end pieces, the right-hand head being numbered 38 and the left-hand head 39. These heads are reduced at their inner ends to fit inside the tube 37 and are secured in place by screws 50. The heads 38 and 39 are provided respectively with outwardly extending hub portions 41 and 42 which are bored out to receive a platen shaft or axle 43, the hub 42 being secured to said shaft by a screw 42^a. At its right-hand end portion, the axle bears in an enlargement or hub 44 which is fixed in the end plate 33. The left-hand end portion of 55 the axle 43 bears in an enlargement or hub 45 secured in the end plate 34. The portion

of the axle projecting leftward beyond the bearing 45 carries a finger wheel 46 of ordinary construction for turning the platen by hand, which wheel is secured in place by set screws 47. The outer end portion of the hub 42 is reduced in diameter and has suitably secured to it a gear wheel 48 for positively connecting the platen with paper feeding devices hereinafter described. The hub portion 41 of the right-hand platen head is extended outward and formed with teeth 49 to provide a pinion that intermeshes with platen driving mechanism hereinafter described. 70

Driven or forced on the pinion so as to have a tight fit therewith is a flanged hub or bearing element 50 to which is fixed a line spacing ratchet wheel 51, the wheel 51 and the part 50 being secured together and acting as a unitary member, which in turn is fast on the hub 41, 49 and consequently rigid with the platen 36. The flanged portion 52 of the ratchet wheel member 50, 51 provides a bearing for the hub portion 53 of a pawl carrier 54, the pawl carrying member 53, 54 being unitary and adapted to turn freely on the flange 52. At its lower end the pawl carrier 54 carries an outwardly projecting pin 55 over which is hooked a spring 56, which at its rear end is anchored to a pin 57 projecting from a bracket 58 which is secured by a screw 59 to the under face of the end bar 29, Figs. 2, 3 and 6. This spring assists in restoring the line space train to normal position after operation. 80

Referring to Figs. 1, 2, 5, 6 and 7, the pawl carrier 54 has pivoted to its upward extension at 60 a line spacing pawl 61 of ordinary construction, which is adapted to coact with the ratchet wheel 51. Said pawl is connected by a forwardly extending link 62 with the long arm of a horizontally disposed bell crank 63 mounted on a screw pivot 64 secured to the end bar 29. The other and shorter arm of the bell crank 63 has connected to it the right-hand end of a link 65 which extends leftward along the carriage and is connected at its left-hand end with the rearwardly extending arm 66 of a line spacing handle member or lever which further comprises a hub portion 67 and a forwardly extending arm or handle portion 68, terminating in a finger piece or handle proper 69. The hub 67 bears rotatably on a pivot 70 upstanding from the left-hand forward corner of the carriage truck. Surrounding the pivot 64, and connected to the bell-crank 63, is a restoring spring 71. The described construction comprising the train beginning with the line spacing handle 69 and terminating in the pawl 61 is the ordinary left-hand line spacing construction of the Remington machine. It will be understood that when the handle 69 is actuated or pressed rightward it will actuate the pawl 61, causing it to cooperate with the ratchet wheel 51 to turn the platen 36 in forward or line 85 90 95 100 105 110 115 120 125 130

spacing direction through a unit of line space distances, and that thereafter continued pressure on the line-spacing handle will operate to restore the carriage and the parts mounted thereon from left to right. Cooperating with the ratchet wheel 51 is a roll detent 72 which is mounted at the forward end of a spring arm 73 that extends rearward and is secured by a screw 74 to a projection 31^a that is integral with the bracket 31. The spring mounted roll-detent cooperates with the line space ratchet wheel to maintain the platen in predetermined positions after line spacing operations and to hold the platen when it is not under actuation.

In addition to the mechanism just described for turning the platen through line space distances, means are provided for turning the platen continuously through a plurality of revolutions, said means comprising speed-multiplying mechanism, next to be described. Intermeshing with the pinion 49 is a driving gear wheel of comparatively large diameter, which is illustrated in Figs. 1, 2 and 3, and which is of ordinary construction, comprising a rim provided with spur gear teeth 75, radial spokes 76 and a hub portion 77. Said hub extends outward and bears at its outer end against a circumferential enlargement on a supporting sleeve or hub 78 which is riveted or otherwise fixed to the end plate 33. On the outwardly extending portion of the hub 77 is mounted a stop member which is in the form of a split collar 79 fixedly secured to the hub by a clamp screw 80. Diametrically opposite to the split in the collar there is provided a radial extension 81 carrying an outwardly projecting lug or pin 82, which is adapted, at the end of the forward turning movement of the wheel, to contact with a stop lever 83 (Fig. 6). The lever 83 is pivoted on a fixed pivot 84 and under the action of the stop 82 is pressed against a pin stop 85 fixed to and projecting inward from the plate 33 so as to positively limit the turning of the gear wheel, the platen and connected parts. The hub or collar 78 is bored out to receive a stub shaft 86. As best shown in Fig. 3, said shaft at its inner end terminates in an enlargement 87 which has a reduced extreme end portion 88, the enlargement 87 thus being in the nature of a flange. Fitted over the flange or enlargement 87 is a split collar 89, which, as will be understood from Fig. 7, is secured rigidly in place relatively to the shaft 86-88 by a clamping screw 90. The collar 89 is provided with two radially extending projections 91 and 92 spaced apart and providing supports for adjustable screw stops or abutments 93 and 94, said stops being held in adjusted positions by lock nuts 95. The oppositely facing ends or points of the screw stops are adapted to coact with a stop pin 96 projecting inward from one of the spokes 76 of the gear wheel or driver 75-77.

A coiled spring 97, anchored at one end to said gear wheel or driving member and secured at its opposite end to a pin 98 on the collar 89, tends constantly to turn said collar and the stub shaft on which it is mounted in counter-clockwise direction, when viewed from the right, and to maintain the screw stop 93 in contact with stop pin 96. The construction is such that if the shaft 86-88 is turned in clockwise direction there will be a lost motion between it and the driving gear wheel 75-77, the extent of which is measured by the distance between the stop 94 and the pin 96. In other words, the turning of the shaft will not affect the gear wheel until the screw stop 94 contacts with the stop 96. For the purpose of actuating the stub shaft 86-88 a crank member or handle is provided comprising a crank arm 99, a hub 100, and a handle proper or finger piece 101. The hub is fitted over the projecting portion of the shaft 86, outside the end plate 33, and is secured to the shaft by a cross pin 102. It will be understood that when the handle 101 is turned, the shaft will be rotated, communicating movement to the collar 89, and thence through the lost motion connection to the driver or gear wheel 75-77 and connected parts, thus turning the platen through the pinion 49 in a direction opposite to that in which the handle 101 is actuated. The stop devices, including the coacting parts 82, 83 and 85, will limit the turning movement of the gear wheel and platen when the platen is being turned to wind on a work sheet. To limit turning movement in the opposite direction there is provided a device 103, which is mounted on the inner face of a disk or circular plate 104. Said device 103 is preferably in the form of a roll, which is adapted to rotate on a bearing pin 105 fixed to and projecting leftward from the left-hand or inner face of said disk 104. The disk is mounted on the inner end of the shaft portion 88 and is held in fixed relationship with said shaft by a pin 106 which is fixed in the flange 87 and projects leftward therefrom, said pin engaging in a hole 107 in the disk 104, thereby fixing the relationship between the disk and the device 103 relatively to said shaft. Leftward displacement of the disk is prevented by a plate or arm 108 which is clamped against the end portion of the shaft part 88 by a clamping screw 109 having a large head, the construction being such that sufficient friction is generated to prevent accidental displacement of the arm 108. Said arm near its outer end carries an actuating pin 110 which cooperates with paper feeding devices as hereinafter described.

Although they do not logically enter into the description at this point it may be well to take up and describe the other parts mounted on the shaft member 86-88 and which are disposed between the disk 104 and the split

collar 89. Said parts, comprising two circular plates or disks 111 and 112, have to do with means for automatically controlling or throwing into and out of use the line space 5 detent roll 72, thereby lessening friction and promoting smoothness and ease of the continuous turning movements of the platen. The circular plates 111 and 112 are best shown in Figs. 1, 2, 3, 6, 7 and 8. The right-hand 10 cam plate 111 is provided with an enlargement or hub portion 113 which is bored out to fit over the shaft part 88. Said cam plate is formed with a circular series of holes 114, there being ten of such holes in the present 15 instance. The holes are adapted to engage with the pin 106, the construction being such that the plate 111 is thus adapted to be set in fixed relationship with the shaft and the parts attached thereto in any one of a number of 20 predetermined relationships. The outer face or periphery of the plate 111 is cut away or depressed, as indicated at 115. The depression having a curved bottom face struck from the center of rotation of the said plate, and 25 the end portions being inclined as shown. The circular plate 111 is also formed with an arcuate slot comprising a narrow portion 116 cut all the way through the plate and also with a wider shallow depression 117 cut part 30 way through. The double slot 116, 117 receives a pair of adjustable members 118 which are independently slidable in the slot-way and serve as nuts for headed screws or stop 35 members 119. The nuts 118 are of a width 40 to seat or fit slidably in the shallow depression 117, thus being housed so as not to project outside the righthand face of the plate 111. The heads of the screws 119 are wider than the narrow portion 116 of the slot, the 45 construction being such that the screws and their cooperating nuts cannot be accidentally displaced from the supporting plate or disk, although they are free to be slid lengthwise of the slotway into various adjusted positions 50 when the screws are loosened. The heads of the screws project leftward into a slotway 120, formed in the other disk or plate 112. The slotway 120 is adapted to register with the slotway 116, and is of substantially the 55 same length. The heads of the screws projecting into this slot 120 serve in effect as stops, and the construction is such that there is provided a lost motion connection between the two disks or plates 111 and 112, the extent of which lost motion is variable according 60 as the stops are set close to or further from each other. The purpose of this construction will be subsequently explained. At this point it need only be said that the plate 65 112 is cut out so as to fit rotatably on the hub 113 of the plate 111, and that the plate 112 is formed with a depression or V-shaped notch 121, the lost motion connection described affording variation in relationship 70 between the notch 121 and the depression 115 in the plate 111. At one of its ends the V-shaped notch terminates in an outward projection or tit 122. It will be understood that by removing the screw 109, the arm 108 and the disk 104 may be withdrawn from the 75 shaft, thus permitting the removal of the two plates 111 and 112. The plate or disk 111 may be reset by bringing the desired hole 107 into engagement with the interlocking pin 106. To facilitate adjustments of the cam plate 80 111, which will depend on the number of forms on the particular bill sheets that are to be employed numbers 1 to 9 may be stamped opposite the corresponding holes 107, in accordance with whether one, two or three or 85 more forms are printed on the particular bill sheets in hand. Also, the screw stops 119 may be adjusted in accordance with the number of lines to be written on each form or blank on the bill. With the parts replaced, a tightening of the screw 109 will hold them in proper relationship. It may be said at this point that the extent of sweep or continuous turning movement of the platen under the 90 actuation of the handle 101, may be limited by varying the relationship between the device 103 and the stop 82, such variation being effected by loosening the clamping screw 80 and turning the split collar 79 so as to vary the circumferential positions of the stop 82 95 relatively to the device 103. This perhaps will be best understood from a consideration of Fig. 6. Preferably, the driver or gear wheel 75-77 is provided with a circular shaped guard or cover plate 123 which is made 100 of sheet metal and is provided with a flange to overlie the periphery of the wheel. The cover plate is provided with enlargements or bosses 124 which receive headed screws 125 whereby the cover-plate is secured to the side- 105 plate 33 of the carriage frame. The cover-plate is disposed inside the plate 33 and spaced leftward therefrom by the bosses 124 so that said cover-plate is brought into the vertical plane of the gear wheel which it 110 covers.

Referring now to the automatic paper clamp which is mounted on the platen, and having reference to Figs. 3, 5, 7 and 8, the tubular platen body 37 is cast with an inwardly projecting rib-like part or enlargement 37^a in which is cut a slot-way 126 which extends longitudinally of the platen and receives the bar-like or body portion 127 of the clamp which is adapted to slide radially in and out of the slot-way 126. Said clamp further comprises a clamping flange or lip 128 which is formed integrally with the body or bar 127 and projects rearward at right angles from said body outside the platen surface, to which the outer face of the lip is curved to conform. The inside or working face of the lip 128 is straight or flat and fits against the corresponding flat surface of an under-cut or depression 129 in the tube 120 125 130

37. The construction is such that when the clamp is closed it hugs the platen tightly and provides an uninterrupted surface, as will be clearly apparent from Fig. 5. Of course, 5 when the paper is inserted between the co-acting flat clamping face 129 and the under face of the lip 128, the clamp will be projected outward slightly away from the platen surface, but not sufficiently to alter materially the regular continuity of the surface and the smoothness of the rotation of the platen will not be affected. Outside the platen heads the bar portion 127 is provided at its lower ends with outward projections or lugs 130 which are somewhat elongated and are rounded off so as to fit rotatively in round openings 131 formed in arms 132 which are pivoted at 133 to the associate platen heads. Nuts 134 threaded on the pivots 133 prevent 20 outward displacement of the arms 132. Each arm carries an outwardly projecting pin 135 over which is hooked a draw-spring 136 anchored at its opposite end at 137 to the associate platen head. The construction is such 25 that the springs acting on arms 132 and, through the pin-and-hole connections 130, 131, on the clamp 127, 128, tend constantly to maintain the clamp pressed toward and engaged with the platen, as shown in Figs. 30 5 and 7.

The clamp is automatically controlled, so 35 that it is opened to receive the work sheet at the end of the rearward work-sheet ejecting movement of the handle 101, and thereafter is automatically snapped shut by the preliminary forward actuation of the handle 101, so as to clamp the paper to the platen before the winding-on operation starts. The 40 automatic controlling means comprises a roll 138 pivoted at 139 to the upper portion of the right-hand arm 132, said roll 138 being adapted to cooperate with a lip 140 inturned from the upper end of an arm 141 pivoted at 142 to the right-hand platen head 38. 45 Through the roll 138 and the lip 140 the pressure of the spring 136 will be transmitted to the arm 141 and normally will maintain said arm in contact with a square stop pin 143 which projects rightward from the 50 platen head 38. In order to open the clamp, the upper rear end of the arm 141 is adapted to contact with a stop 144, which is formed by a forward projection at the lower end of a cam and stop member 145. This member, 55 as shown in Figs. 3, 6, 7 and 8, is preferably formed of a single piece of sheet metal. Its lower end portion is bent in the shape of a U so as to provide a yoke comprising a cross portion 146 and an upwardly bent portion 60 147, which is parallel with the body portion of the member 145, but is disposed some distance to the right of it. This portion 147 terminates at its rear in a stop face 148. The portion 147 and the opposite portion of the 65 body of the member 145 are perforated to

fit over and bear rotatably on a stub shaft or rod 149, which at its right-hand end is secured to the end plate 33 by a screw 150. Said shaft thence extends leftward and its inner end bears in an angular bracket 151 which is secured to the rear bar 28 of the carriage truck by screws 152. It may be said at this point that there are a pair of these brackets 151 arranged one near each end of the carriage. In order to complete the description of the member 145, it may be stated that it further comprises a downwardly extending stop lug 153 and that the body of the member extends upward and terminates in a hook-like head 145^a which is formed with an open-mouthed cam-slot 154 terminating in a dwell portion 155, the cam slot and the dwell fitting over and being adapted to cooperate with the roll or controlling device 103. The member 145 is adapted to be maintained in normal position by a coiled spring 156, the forward end of which is hooked over a lug 145^b on the member 145, the rear end of said spring being anchored to a bracket 157 which is clamped by the screw 74 against the upper face of the detent arm 73. The bracket 157 is provided with a curled bearing portion 158 which is tapped to receive an adjustable screw stop 159. Said spring 156 tends constantly to maintain the stop face 148 in contact with the forward end of the screw stop 159. The member 145 has pivoted to it at 160 a spring latch 161 having a tail portion which is connected by a draw spring 162 to the lug 145^b. This spring tends constantly to maintain a lip 163 bent horizontally from the forward end of the latch in engagement with a shouldered edge 164 on the top of the part 144. The front portion of the latch 161 terminates in an incline or cam edge 165. Under normal conditions the member 145 will be held in the position shown in Fig. 6 with the stop 148 engaged with the stop 159. In the course of the ejecting rotation of the platen to unwind a written work sheet, the roll or stop device 103 will be brought into engagement with the forward edge of the cam slot 154 and will swing the member 145 forward about its pivot 149 so as to bring the cam edge 165 and also the stop 153 into the path of the stop 143, which is being rotated in clockwise direction with the platen as the parts are viewed in Fig. 8. As the ejecting movement of the platen continues, the upper corner of the stop 143 will engage with the edge 165 and will swing the latch 161 up above its pivot 160 against the pull of the spring 162 until the latch rests on the top of the stop pin 143. As soon as the pin 143 clears or passes the latch, said latch will be snapped down by its spring over the front side of the pin which at this time will have engaged at its rear face with the stop 153. As will be apparent in Figs. 7 and 8, the parts

are so arranged that this effects an interlocking engagement between the square stop pin 143 on the one hand and the member 145 and latch 161 on the other hand. Meanwhile, as the pin 143 starts to engage with the cam edge 165 the arm 141 will engage at its upper rear end with the stop 144 so that as the turning movement of the platen continues the arm 141 will be forced forward about its pivot 142, causing the lip 140, acting on the roll 138, to swing the arm 132 forward about its pivot 133 and thus force the clamp 127, 128 outward in its bearing. This operation, it will be understood, is in opposition to the springs 136 at both ends of the platen. The parts are so proportioned and timed that after the member 145 has been cammed forward to operative position by the coaction of the roll 103 with the cam slot 154, the roll will enter the dwell 155, so that the member 145 will remain stationary during the opening of the clamp and the operation of the latch 161 including its snapping down in front of the pin 143. The parts at this time will be in the position illustrated in Fig. 8. From this figure, it will be understood that both the disk 104, carrying the roll 103, and also the platen were rotated from the handle 101, the platen through its connection with the driving gear. With the clamp open, as shown in Fig. 8, the paper may be inserted as hereinafter more particularly described and the mechanism is then ready to have the clamp closed in order to grip the paper to the platen, which thereafter is to be rotated in counter-clockwise direction, viewed from the right, in order to wind the paper thereon. As has been stated, it is necessary to clamp the paper promptly before the platen begins to move and the mechanism described is effective for this purpose, as will be understood from the following. The paper having been inserted, pressure against the operative handle 101 is reversed, that is, it is pulled in clockwise direction, thus causing the roll 103 to move down out of the dwell 155, and act against the rear or under edge of the cam slot 154, swinging the member 145 upward and rearward about its pivot so as to lift the stop 144 out of engagement with the arm 141. Until this operation is completed, the platen will be held rigidly against the movement by the cooperation of the pin 143 with latch 161 and the stop 153. It will be apparent that as soon as the stop 144 clears the arm 141, the clamp will be snapped or forced down into clamping engagement by the action of its springs 136 into the position shown in Fig. 7. From this figure, it will be seen that this clamping action takes place before the platen has been released by the disengagement of the latch 161 and the stop 153 from the pin 143, these parts operating in effect like clutching jaws on the pin. It will also be apparent from an examination of Figs. 7 and 8 that

this preliminary clamping operation is permitted to take place prior to any moving force being applied to the platen because of the lost motion connection between the devices 93 and 94 and the pin 96. Positive rotary movement of the platen to wind on the paper will not take place until the pin 94 has moved downward into contact with the pin 96, thereby picking up the driver or gear wheel 75-77 and actuating it to rotate the platen. 70 75

Devices are provided to cooperate with the circular plates 111 and 112 to control the automatic throwing off and on of the line-space detent-roll 72, during the back and forth rotary movements of the platen. Said devices comprise an arm or lever member 166 (Figs. 2, 3, 6 and 7) which is provided at its lower end portion with a U-shaped offset or yoke comprising a cross portion 167 and an angular part 168 bent up parallel with the body portion of the arm 166. The part 168 and the body portion near its lower end are perforated to fit over the stub shaft 149 on which shaft the arm 166 rotatably bears, it being disposed between the end plate 33 and the yoke portion of the cam member 145, as best shown in Fig. 3. The upper end portion of the arm 166 is off-set leftward and at its upper end carries a pin 169 which provides a bearing for a roll 170, so disposed that it overlies the periphery of the plates 111 and 112 and is adapted to cooperate therewith. A pin 171 projects leftward from the arm 166 and underlies the spring arm 73, being so related to said arm that when the arm 166 is swung rearward about its pivot 149, the pin 171 will act against the under side of the arm 73 and will lift the detent roll 72 out of engagement with the ratchet wheel 51, as will be clear from Fig. 7. The pin 171 will be thus effective when the roll 170 is riding on the outer circular faces or peripheries of the plates 111 and 112. On the other hand, when the depressions 115 and 121 permit the roll 170 to move forward, this allows forward swing of the arm 166 which will be pressed down by the spring action of the arm 73 on the pin 171, permitting the detent roll 72 to re-engage with the ratchet wheel 51. 90 95 100 105 110 115 120 125 130

The operation of the devices comprising the arm 166 and the disks or plates 111 and 112 may be briefly referred to. Normally at the start of the operation of winding on the bill sheet the roll 170 will be engaged with the peripheries of the plates 111 and 112, thus holding the detent 72 out of engagement and promoting the free rotation of the platen. This will be understood from a consideration of Figs. 2 and 7. As the platen nears the end of its winding-on operation, the tip 122 will be brought into engagement with the roll 170 and will hold back the plate 112 until said plate is picked up and forced to

turn by the engagement of one of the stops 119 carried by the plate 111 with the neighboring end of the slot 120 in the plate 112; or in other words, until the lost motion between the two plates is taken up. Thereafter further turning movement will force the roll 170 up over the tip 122 and permit to drop down into engagement with the notch 121, thereby permitting the detent roll 72 to engage with its ratchet wheel 51. This operation takes place approximately at the end of the forward or winding on movement of the platen under actuation of the handle 101. The position of the parts at this time is illustrated in Fig. 6. Thereafter as the lines are written on the bill and the platen is line spaced from line to line, the plate 112 will remain quiescent, the roll 170 remaining in the notch 121 and the detent 72 consequently acting on the ratchet wheel 51 to control the line space positions of the platen. It will be recalled, however, that during these line spacing movements, the plate 111 will be rotated and eventually the other stop 119 carried thereby will act against the end of the slot 120 to pick up the plate 112, forcing it to turn. As a result the roll 170 will be forced out of the notch 121 and caused to ride on the outer periphery of the two plates 111 and 112, thus automatically lifting and maintaining the detent 72 cut of the ratchet wheel 51 so that the continuous retracting or unwinding movement of the platen under operation of the handle 101 will not be interfered with.

As has been stated, the extent of the lost motion between the two plates 111 and 112 may be regulated by adjusting the stops 119 relatively to each other. From what has been said, it will be apparent that this regulation will depend on the number of lines to be written on each of the set of forms or blanks on the bill sheet. It will be seen that means are provided for automatically rendering the line space detent devices effective when the writing of the bill is to be begun, and for automatically rendering them ineffective when the writing has been completed, and that such means are adjustable to accord with the number of lines on the bill, or with the number of line-to-line spacing operations.

It will be apparent that during the winding-on of the bill sheet, it will be positively connected to the platen and caused to be wrapped around the same primarily through the paper clamp 127, 128. After the bill has been written, however, and it is desired to eject it rapidly, the clamp is of no assistance, and accordingly there have been provided feeding devices which are thrown into effective position and positively connected to the platen automatically when the platen approaches the end of the winding-on operation, so that the feeding devices may cooperate with the bill to advance it during line

spacing operations and also during the subsequent continuous ejecting operation. As shown in Figs. 1, 2, 6, 7 and 8, the paper feeding devices comprise knurled metal rolls 172 fixedly secured one near each end of a shaft 173 which extends longitudinally of the platen above the printing line, the rolls being so disposed as to cooperate with the face of the platen near its ends. The shaft 173 is mounted near its ends on a pair of downward curving arms 174 which at their lower ends are provided with outwardly extending collars 175 which fit over and are fixedly secured to a rock shaft 176 which bears at its ends in the plates 33 and 34 of the carriage frame. Crank arms 177 upstanding from the collars 175 are formed with holes through which are hooked the forward ends of draw springs 178. The rear end of the left hand spring is anchored to a pin 179 projecting inward from the side plate 34, while the rear end of the right-hand spring 178 is anchored to an arm 58 integral with the bracket 58. The springs tend constantly to turn the shaft 176 in a direction which will press the feed rolls 172 into engagement with the surface of the platen. Mounted on the left-hand end of the shaft 173, outside the arm 174, is a pinion 180 which lies in the same fore-and-aft plane as the gear 48 and is adapted to intermesh therewith when the feed rolls 172 engage with the surface of the platen or the paper thereon. The construction is such that the feed roll shaft 173 is positively connected with the platen through the gear 48 and pinion 180, so that when the platen is turned, it will positively turn the feed or pressure rolls 172, causing them to coact to feed or advance the paper passing between them.

In order to lock the feed rolls 172 out of operation during the winding-on of the bill when they would be superfluous, means are provided comprising lugs 181 extending outward from the arms 174 and adapted to be engaged by hooks or arms 182 which extend rearward from and are secured to a rock shaft 183 that bears in angular brackets 184 secured by screws 185 to the front part of the carriage. A spring 183^a coiled around the rock shaft and acting thereon, tends constantly to press the hooks or arms 182 downward. Secured to the right-hand arm 182 by screws 186 is an upstanding finger 187 which at its upper end portion is off-set to lie in the path of the pin 110.

The operation of the means for automatically controlling the paper feeding mechanism is as follows: When the clamp 127, 128 is open to receive the work sheet, as shown in Fig. 8, it will act against the feed rolls 172 to force them away from the surface of the platen and cause the hooks 182 to snap down over the lugs 181 which will operate to maintain the feed rolls in inoperative position during the subsequent winding-on of the bill.

As the end of this winding-on approaches, the actuating pin 110 will engage with the finger 187 and will force it upward and forward about its pivotal center 183, thereby lifting the locking hooks 182 and permitting the feed rolls 172 to be swung forward by the spring 178 into cooperative engagement with the platen at the same time that the pinion 180 engages the gear 48. The parts are so timed that this operation takes place approximately at the end of the winding-on operation.

One of what may be called the "safety" devices incorporated in the machine comprises means for preventing the billowing mechanism from being operated in a direction to wind on a bill sheet unless such bill sheet has been actually clamped in place on the platen. The means aforesaid comprise, as shown in Figs. 1, 2, 3, and 5, an arm 188 provided with a hub 189 which fits over and bears on a rod or shaft 190, said shaft being secured in a tubular support or nut-like member 191 which cooperates with a screw 192 to maintain the parts in fixed relationship with the end plate 34. The rod projects inward from the end plate and underlies the platen near its left-hand end. A collar 193 is secured to the right-hand end of the rod 190 and has anchored to it a wire spring 194 which is coiled around the rod and is connected to the arm 188, tending constantly to draw the forward end of said arm upward. Said forward end terminates in a tooth or pawl 188^a which registers with a depression 195 formed in the left-hand end portion of the platen surface. The outer or free end of the arm 188 carries a pin 196 on which is rotatably mounted a roller 196 which is adapted to ride on the surface of the platen, it being constantly pressed there-against by the spring 194. The roller 196 is also adapted to engage with the depression 195, and the construction is such that if there is no paper in the machine, the roller riding down in the depression will permit the pawl or detent tooth 188^a to engage with the edge of said depression after the platen has been only slightly turned in winding-on direction, such engagement positively arresting the platen and preventing operation of the mechanism. It will be further understood that when a bill sheet has been clamped to the platen, it will bridge or cover over the depression 195 therein so that the roller 196 will not drop. Thus the pawl will be held out of engagement with said depression when the platen is turned, and will be ineffective to lock the mechanism against operation.

Referring now to the means for carrying and controlling the reproducing material, preferably carbon paper, such means are best shown in Figs. 2, 3, 4, 5 and 7.

The reproducing material or carbon paper, indicated by the numeral 197, is ordinarily supplied in roll form, being wound on a paste-

board core or tube 198. There is provided a tubular holder or carrier for the roll of carbon, said carrier or holder comprising a hollow tube or cylindrical body portion 199, within the ends of which are received heads or end pieces. The right-hand head 200 fits within the tube and is suitably fixed in place, it being formed with a hub portion 201 to fit over the support or bearing for the roll holder, and the flanged end of the head 200 being provided with a series of teeth 202, forming a crown gear wheel.

Projecting inward from the head 200 is an extension 203 rounded at its end to facilitate the fitting over it of the pasteboard core 198 and preferably formed with a number of longitudinally extending kerfs or slits to promote resiliency, so that the core 198 will frictionally engage with the projection 203, and will be held against accidental turning movements thereon. The left-hand end of the tubular body 199 is provided with a detachable head or end piece designated as a whole by the numeral 204. Said end piece comprises a head proper 205 having secured to its periphery a knurled ring or annulus 206. The head proper has integral with it an inwardly extending flanged portion 205^a. Also integral with the head is an inwardly extending hub portion 207, over which is fitted and securely held an additional extension 208 which is likewise formed with longitudinal kerfs indicated at 209, thus dividing the extension into a number of resilient fingers which are curved at their free ends to provide a nose so as to engage readily with the core 198 and hold it frictionally. The detachable head 204 is adapted to engage with the tube 199 by a bayonet joint, and a latch is provided for preventing the joint from slipping accidentally. Said latch is in the form of a curved or arcuate spring arm 210 secured by a screw 211 to the inner face of the flanged portion of the head 205. The free end portion of the spring arm 210 projects outward through a slot 212 formed in the flange 205^a, and this outwardly projecting portion is adapted to be drawn inward by hand below the surface of the flange 205^a by means of a laterally extending finger piece 210^a, which is integral with the spring arm 210 and extends through a hole or slot in the vertical outer face of the head proper 205. The bayonet joint comprises a right angled or bayonet slot 213 formed in the left-hand end portion of the tube 199, said slot cooperating with a screw or stop 214 secured in the flanged portion of the head 205. The construction is such that when the head and the tube are interlocked, as shown in Fig. 3, the spring arm or latch 210 projecting upward through the slot 213 will prevent relative rotation of the parts such as would bring the screw 214 opposite the outwardly extending or mouth portion of the slot, so that the head

could be detached. In order that separation of the parts may be accomplished, it is first necessary to depress or withdraw the latch by pressing down on the finger piece 210^a.

5 Preferably the spring latch 210 is covered at the right by means of a disk 215 which is suitably secured to the inner end portion of the flange 205^a. The knurled annulus 206 affords a convenient means for turning the 10 head 204 on the tube 199 so as to connect and disconnect them. It will be understood that when the roll holder has been detached from the machine as hereinafter explained, it is only necessary to remove the head 204 to enable 15 a roll of carbon to be inserted and its core 198 fitted over the projection 203 at the right, after which the head 204 may be replaced, the extension 208 fitting inside the core at the left, the core being thus suitably supported and the carbon roll housed inside 20 the hollow cylindrical holder. Said holder is formed longitudinally with a slot-way indicated at 216 open at the left, and of course in inserting the roll of carbon, care must be taken first to unwind sufficient of it to enable 25 the unwound portion to pass through the slot and be moved along rightward with the carbon roll as it is mounted in place in the holder, leaving the loose free end outside of 30 the slot 216. The cylindrical carbon holder is made preferably of aluminum and is of substantially the same diameter as the platen. It will be understood, of course, that the supply roll wound on one of the core pieces 35 198 is sufficient to write a large number of bill sheets. In making use of the device initially, it is intended that only an amount of carbon paper 197 be unwound from the roll and drawn outward through the slotway 40 216, which will correspond in length with the length of one of the multiple bill sheets 7, allowing for the distance from the roller or carrier to the platen. This free or unwound part of the carbon paper is wound on 45 the outside of the tubular body 199 of the holder, and it will be understood that the number of winds or wraps of carbon thereon correspond with the number of winds or wraps of the bill sheet on the platen. From 50 what follows it will be seen that the carbon is wound on and off its carrier or holder in correspondence with the winding on and off of a bill sheet on the platen, so that the two sheets may be interleaved, enabling the carrier 55 to reproduce impressions on all of the bill forms underlying the outermost form or wrap. It is the purpose of course to use the same unwound portion of the carbon until it is so far exhausted that it will not adequately 60 offset on the bill sheet so as to make clear copies. When thus exhausted it is only necessary to withdraw through the slot 216 a fresh supply of carbon paper, tearing off and discarding the used portion. By this construction 65 the carbon carrying roller carrying the outside portion of the carbon that is in use is always maintained of substantially the same diameter as the platen, whatever the size of the roll of carbon inside the holder or roller may be. The carbon roll holder is disposed above and at the rear of the platen, 70 being mounted on a shaft 217 which is supported at its ends in the side plates 33 and 34. At its right-hand end the shaft 217 is adapted to bear in a bearing hub or block 218 which is riveted or otherwise secured in the plate 33. In order, however, that the carbon roll holder may be readily withdrawn from the machine, it is necessary to provide a different form of support for the left-hand 75 end portion of the shaft 217. To this end the bearing hub 219 at the left is secured in a detachable circular plate or disk 220 which is shouldered, as indicated at 221, to fit in a circular hole or opening 222 formed in the plate 34. The disk 220 is provided with a number, four in the present case, of round holes 223 whereby the disk may be conveniently grasped and manipulated. Secured to the inner face of the disk as by rivets 224 is a strap 225 projecting at its ends slightly 80 beyond the shouldered portion 221 of the disk, and these projecting portions are adapted to cooperate with the inner wall of the plate 34 so as to interlock the disk 220 therewith and hold it firmly in place. Openings or recesses 226 diametrically opposite each other are provided opening into the hole 222, and it will be understood that when the disk 220 is rotated so as to bring the strap 225 in line or register with these openings 226, the disk may be pulled outward and detached from the plate 34, this removal of course carrying with it the bearing 219. The opening 222 is of sufficient diameter to enable 85 the carbon holder to be withdrawn through it. In order to hold the holder and the detachable bearing, comprising the bearing proper 219 and the disk 220, in proper relationship, said bearing is formed with a circular groove indicated at 227 into which is adapted to fit a curved plate 228 which is secured by screws 229 to the head 205 in such a way as to be offset slightly to the left of the outer face of said head and so as to register with and engage slidably in the groove 227. It will be understood that when the circular plate is engaged with the groove, the two parts are properly in register and connected together and may be applied to 90 and removed from the bearing shaft 217 at one operation. 95

As has been stated, the platen and the carbon holder or rotary carrier are of the same diameter. The carbon holder is connected to the main driving gear 75 and 77 by the same sized pinion as employed for the platen connection, and consequently the holder is driven or rotated at the same speed as the platen. However, at the start of the wind- 100

ing-on operation the platen is bare and the holder is increased in diameter by the thicknesses of carbon paper wound on the outside of the tube 199. As a consequence, as the 5 diameter of the platen increases through the winding-on of the paper and interleaved carbon, and the diameter of the carbon holder lessens by the winding off of the carbon paper, there would occur a pull on the carbon 10 between the holder and the platen, which would tend either to act as a drag or brake on the mechanism, or might result in rending or tearing the carbon. To avoid this defect, there is provided a yielding connection be- 15 tween the carbon holder and its connection with the driving gear. Said connection comprises a pawl carrying member 230 which is fitted loosely over the shaft 217 at the right of the carbon holder and is provided at dia- 20 metrically opposite ends with leftwardly ex- tending teeth or pawls 231 which are adapted to engage between the teeth of the crown gear wheel 202. Said pawl carrier is con- 25 stantly urged leftward into engaging posi- tion by a spring 232 coiled around the shaft 217. The leftward effect of the spring is limited by a collar 233 fast on the shaft 217 and interposed between the hub 201 and the pawl carrier 230. The spring 232 is inter- 30 posed between the pawl carrier and a spring drum or box 234 which is slidably mounted on the shaft and comprises an inner hub 235 and an outer flange 236. Fitted over and bearing rotatably on the hub 235 as well as 35 partly on the shaft 217, is a pinion 237. In- side the drum 234 is arranged a coiled band spring 238 one end of which is connected to the flange 236 of the drum, and the opposite or inner end to the pinion 237. This spring 40 tends constantly to turn the pinion forward relatively to the drum and to maintain a ra- dial stop pin 239 on the pinion in contact with a stop pin 240 projecting radially in- 45 ward from the inside of the flange 236 of the drum or housing 234. In other words, the driving pinion is thus provided with a yield- 50 ing or resilient connection with the drum 234. The drum is connected with the pawl carrier 230 so as to communicate motion through it to 55 the carbon holder by mean of a pair of left- 60 wardly projecting pins 241 which are secured diametrically opposite each other to the left- 65 hand end of the drum 234 and engages loosely 70 in slots 242 in the pawl carrier 230. Heads 75 243 on the left ends of the pins 241 are dis- 80 posed to the left of the pawl member 230, these heads being of sufficient diameter to 85 prevent disconnection of the pins from the pawl carrier while permitting some freedom 90 of longitudinal movement of the pawl carrier 95 and also relative movement between the drum 234 and the pawl carrier lengthwise of the shaft 217. A flanged ring 244 is driven on 100 the pinion 237 to the right of the spring 238 105 and provides a suitable closure for the right- 110

hand end of the spring drum 234. When the parts are assembled in place, as will be under- 115 stood from Fig. 4, the right-hand end of the pinion 237 abuts against the stationary bearing hub 218, thus in effect causing the spring 232 to re-act against the pawl member 230 and maintain its teeth engaged with the gear teeth 202. The shaft 217 at this time is held against longitudinal movement by a screw stop 245 which is threaded into the hub 218 120 and coacts with a flange 246 on the shaft, said flange forming the right-hand side of a groove or depression 247 in the shaft, the construction being such that the shaft has endwise play equivalent to the width of the groove 247. With the parts positioned as shown in Fig. 4, it will be understood that the pinion 237 intermeshes with the driving gear 75—77 (Fig. 2) and that motion will be transmitted to the carbon roll carrier from 85 the driving gear by the train of mechanism as described. 90

When it is desired to release the carbon roll holder to provide for a fresh supply of carbon, the left-hand projecting end of the shaft 217 is pushed rightward, causing the right-hand end of said shaft to project be- 95 yond the end plate 33 and exposing a narrow circumferential groove 248 cut in said shaft near its right-hand end. As soon as the 100 grooved part of the shaft is forced outside the end plate, it is engaged by a pivoted lever member or detent 249, Figs. 2, 3 and 4, so as to hold the shaft in its abnormal position. The lever member 249 is pivoted on the out- 105 side of the end plate 33 and 250 and has a limited movement on said pivot equal in ex- 110 tent to the play of a pin 251 carried by said lever member in a slot 252 cut in the end plate and with which said pin engages. A flat 115 spring 253 having an ear 254 secured by a screw 255 to the inside of the end plate bears at its free end on the pin 251 tending con- 120 stantly to press down the engaging end of the lever member 249, the construction being such that the lever member or detent will snap into the groove 248 as soon as it is ex- 125 posed, thus locking the shaft 217. The for- 130 ward end portion of the lever member is pro- vided with a cam face 256 which is adapted to be engaged by a pin 257 projecting inward from the handle arm 99, so that if the oper- 135 ator should neglect to release the detent, the pin will operate automatically to depress its front end and swing up its rear end during the initial stage of movement of the handle 101, thus automatically releasing the shaft which will be pressed leftward by the spring 232 to reconnect the driving mechanism with the carbon roll holder. The purpose of push- 140 ing the shaft 217 rightward is to cause the collar 233 fixed thereto to act against the pawl carrier 230, pressing it rightward, compress- 145 ing the spring 232, and disconnecting the teeth 231 from the gear 202 so as to leave the 150

carbon holder free to be rotated in order that a fresh supply of carbon may be drawn from the inside of the holder and wound on its outer surface.

In order to guide and feed or unwind the carbon paper smoothly off the outer surface of the roll holder, a feed roll mechanism is provided which as best shown in Figs. 2, 4, 5 and 7, comprises a roller proper 258 made of yielding material and mounted on a shaft 259 which is provided with flanges 260 to confine the roll 258 in place. The outer end portions of the shaft bear detachably in clips 261, which are formed at the end portions of a unitary sheet metal support 262 that has a limited rotary movement on a pivot 263 riveted or otherwise secured to the lower central portion of a yoke 264, which yoke has secured to it by screws 265 a curved clamping plate 266 that embraces a rod or shaft 267 bearing at its ends in the end plates 33 and 34. By removing the screws 265 the yoke may be separated from the bearing plate and detached from the machine, carrying with it the support or clip carrier 261, 262 and the roll 258. The clip carrier 262 is prevented from being detached from its pivot 263 by a cross pin 268. Interposed between the clip carrier and the yoke 264 at opposite sides of the pivot are small bearing balls 269 which interseat in depressions formed oppositely in the two opposing parts, these depressions being so shaped as to permit a slight movement of the clip carrier and feed roller 258 about the pivotal center 263. This permits the roller to seat properly on or against the carbon roll holder to cause the parts to properly cooperate when the roll holder is turned to feed or advance the carbon paper. Spring pressure is transmitted to the roller 258 from the shaft 267 on which the yoke 264 is rigidly secured by the screws 265 and clamping plate 266. This spring pressure is obtained from spring means cooperating with the left-hand end portion of the shaft, Figs. 2, 4 and 7. Secured to the projecting left-hand end portion of the shaft 267 is a crank arm 270 (Fig. 4) provided with a hub 271 fixed to the shaft by a screw 272, said screw terminating in a finger piece whereby the shaft may be partly rotated by hand. The lower end of the crank arm 270 has secured to it one end of a coiled spring 273 (Fig. 4) the opposite end whereof is secured to a latch piece 274 pivoted to the outside of the end plate 34 at 274^a and notched at 274^b as shown in dotted lines in Fig. 7 to engage with a pin 275 on the crank arm to hold the shaft and the carbon feed roller out of operation when desired. Ordinarily the effect of the spring 273 is transmitted through the shaft 267 to the roller 258 to press it against the carbon roll holder or the carbon paper thereon.

The forward end portions of the bracket

arms 151 (see Fig. 5) are twisted vertically and terminate in head-like portions 151^a having inclined faces 276. Pivoted at 277 on the inner faces of the heads 151^a are ears 278 bent down from the end portions of a guide plate 279 which rests on pins 280 projecting inward from the heads 151^a. The guide plate 279 serves to receive and support the free end portion of the carbon paper 197 as it passes downward and forward from between the roll holder and the feed roll 258. The parts are so adjusted that when the carbon re-winds on the roll holder during the operation of the machine, the end portion of the carbon is left so that it will lie in position to fall into or just back of the space between the clamp 128 and the coacting surface 129 when the clamp is opened to receive the work sheet. This will be best understood from a consideration of Fig. 5.

The work sheet 7 having been, as heretofore stated, withdrawn at its feeding-in end portion from the magazine 1 is led down to the platen over paper guiding devices which constitute in effect a chute and comprise an inclined sheet metal plate or table designated as a whole by the numeral 281 and shown in Figs. 1 to 5. The body portion or plate 282 of the table is of a width to accommodate the sheets commonly employed in practice. Mounted on the upper face of the body or plate proper 282 are side guides or plates 283 of which the right-hand one has lugs 284 projecting downward through cross slots 285 which hold the right-hand guide 283 in proper vertical position. Said guide is provided with horizontal extensions 286 which receive clamping screws 287 that are adapted to slots in the plate 282 and afford adjustments of the right-hand plate 283 towards and away from the left-hand guide plate 283, so as to provide the correct width for the passage of the work sheet as it is guided downward. Said sheet in its downward course passes between the upper face of the plate 282 and guide members designated as a whole each by the numeral 288, said guide members being formed of sheet metal and being divided by vertical parallel cuts 289 into fingers 290 which at their lower ends are adapted to engage loosely in cross depressions 291. The finger portions 290 are shown as riveted to the body portions, but it will be understood that if desired the parts 288 may be unitary. Secured to the upper curved portions of the bodies 288 and extending over and down behind the same are supplementary fingers 292 which press lightly against the face of the plate 282. The whole construction is designed to guide the down-coming work sheet or form lightly and evenly over the table 281. So guided the lower end portion of the sheet will be brought into position to be engaged by the clamp 127, 128 when it is opened and in the position shown in Figs. 130

5 and 8. The table member 281 rests normally at its lower end on the inclined faces 276 of the brackets 151, 151^a. The paper table as a whole is pivotally supported on the cross rod or shaft 267 and to this end is provided at its rear side with bearing blocks or projections 293 which terminate in outwardly extending hubs 294 (see Fig. 4) which fit over said rod and over end pieces 295 which prevent lateral displacement of the paper table on its pivotal support. The end pieces 295 and hubs 294 are held rigidly united to turn on the shaft 267 by screws 295^a. Said table is normally held in operative position by means of detent members 296 rigid with said end pieces and formed with notches 297 and 298 to accommodate detents 299 mounted at the ends of a rock shaft 300 pivoted in the end plates 33 and 34. Normally the detents 299 engage with the notches 297, holding the table in operative position. A coiled spring 301 (Fig. 2) holds the detents in engaging position. The right-hand detent 299 is provided with a finger piece 302 whereby the detents may be withdrawn from the notches 297, permitting the paper table to be thrown back about its pivotal axis, the detent notches 298 engaging with the detents to hold the paper table in its thrown-off position, thus exposing the underlying mechanism. The rear sides of the notches 298 are so shaped that the paper table may be pulled forward to restore it to normal position without requiring any manipulation of the detents 299 through the controlling finger piece 302.

The paper table 281 also provides guiding devices for receiving the work sheet after it has been written and as it is fed off the platen during the continuous ejecting movement thereof. Said devices comprise the curved upper end portions 288^a of the members 288 which act to receive the top edge of the sheet as it is fed upward. The upwardly advancing edge of the sheet is guided to these curved portions 288^a by guide plates 303 secured to the lower side edges of the plate 282 and extending inward therefrom, said plates 303 being off-set forward to provide a receiving opening indicated in Fig. 5 by the numeral 304. Integral with the guide plates 303 are upwardly extending fingers 305 which are so shaped as when the upwardly advancing paper is received by the curved guides 288^a and thence directed downward, it will be caught by these fingers 305 and directed downward to the root portions 306 thereof and thence again directed upward. It will be recalled that the work forms 7 are creased or folded crosswise between blanks. The receiving and guiding devices, comprising the parts 288^a, 305 and 306 are so disposed and shaped that they will automatically fold the feeding-out work-sheet along these creases so that when it is released from the platen and discharged, it will lie within the receiv-

ing guides and between the parts 288^a and 305 resting on the fingers 309 in folded condition, enabling it to be conveniently removed through the space between the lower edges of the curved parts 288^a and the upper ends of the fingers 305. 70

Finally, safety devices have been provided which will lock the mechanism against operation unless the carriage has been moved to the limit of its right-hand travel, in which position it will be in accurate register with the stationary magazine 1. This is an important feature, since if it were possible to operate the winding-on mechanism when it was not in exact register with the paper as it was brought down from the magazine, there would be an inevitable tendency to feed crookedly, resulting in the irregular winding-on that is commonly referred to as "spiralizing". The safety devices referred to are shown clearly in Figs. 1, 2, 3, 5 and 7. These comprise a cap 307 which fits loosely over the outwardly projecting boss 44 and is secured to and in fixed relationship with the outer end portion of the platen axle or shaft 43 by a shoulder screw 308. The shouldered portion of this screw is square or hexagonal and fits in a corresponding hole in the cap, so that the cap is forced to rotate with the shaft 43. The cap is formed with an integral radial extension or finger portion 309 which is adapted to coat with a notch 310 formed in the upper rear end portion of an arm 311 which extends forward outside the end plate 33 and is secured to the outwardly extending end portion of a short rock shaft 312 which extends inward through the end bar 29 and bears rotatably therein. Fixed to the inner end of said rock shaft inside the end bar is a hub 313 having a projecting nose 314 which is adapted to be engaged by the right-hand end portion of a pivoted plate 315. Said plate is provided with upward extensions 316 which are secured in the stiffening rod 317, the rod and plate being disposed behind and longitudinally of the front bar of the carriage. The extensions 316 are provided with outwardly extending lugs 318 which bear in perforated ears 319 depending from the angular brackets 184. The plate 315 is adapted to be actuated by a finger or extension 320 which is secured by rivets 320^a to a pivoted arm 321, which is part of the regular line locking train of a No. 20 Remington type-writing machine and is adapted to be turned pivotally under certain conditions. The margin stops 322 are of the usual construction and need not be described in detail. The stationary stop 323 has a pivot 324 and is provided with a downwardly extending finger 325 which operatively engages with the pivoted member 321. The stop 323 is connected through the finger 325 with the member 321 in such a way that when the stop is turned on its pivot 324, the member 321 80

85

90

95

100

105

110

115

120

125

130

will be turned on its pivot. In the present case the stop 323 is thus turned automatically during the rightward movement of the carriage. For this purpose the usual carriage-carried margin stop 326, which is adjustable along the front bar of the carriage in a manner well understood, is provided with a special incline or cam face 326^a which is adapted to coact with the upper arm of the frame stop 323. The adjustable carriage stop 326 during the rightward movement of the carriage will engage at its cam or beveled face 326^a with the stop 323 and exerting a cam action thereon will swing its upper end portion forward, the finger 325 being moved rearward and acting on the member 321 which will cause the extension 320 to swing the plate 315 rearward on its pivots 318. As the plate is swung rearward its right-hand end portion acting against the nose 314 will rock the shaft 312 and swing the arm 311 downward so that the notch 310 therein will disengage from the finger 309, thus releasing the platen shaft 43 so the platen may be turned. It will be understood that at all times other than when the stops 323 and 326 are operatively engaged at the end of the right-ward movement of the carriage, the locking arm 311 will be maintained up in operative position. This is due to a constantly acting flat spring 327 which underlies the end bar 29 and is secured thereto by screws 328. Said spring has an outwardly extending end portion 329 which underlies the arm 311 and tends constantly to swing it upward. It is only when this spring is overcome by the coacting carriage stops 323 and 326 in the manner described that the locking arm 311 is swung down to its non-working position.

The various features of the operation of the invention have been explained and discussed in connection with the description of the different mechanisms which combine to constitute the invention as a whole, and it is thought therefore that a further detailed lengthy description of the mode of operation is unnecessary. It will be understood that in making use of the multiple-billing mechanism constituting the invention the operator first pushes the carriage to the extreme right-hand position, causing the stops 323 and 326 to coact to arrest the carriage, said stops also effecting a downward throw of the locking arm 311, thus freeing the finger 309 so that the platen may be rotated. As a result the paper guiding devices on the carriage or traveling paper carrying device are registered with or in line with the magazine, stationary supply device or source of supply 1, so that the top bill sheet in the pile of folded sheets in the magazine or source of supply may be brought down from said magazine as heretofore explained and introduced through the chute, that is, over the paper table 281, pass-

ing under the guide fingers 290, and being brought into position with the lower or bottom edge of the multiple-bill sheet 7 in position to be gripped by the platen clamp. As has been explained, the free end of the carbon 197 overlying the guide plate 279 behind the table 281 will have its free end in line with the free end of the bill sheet and behind the same. The clamp 127, 128 will then be opened through the cooperation of the parts, including the arm 144, as has been explained. In order to afford full stroke of said arm the hub 41 may be grooved as indicated at 41^a. A continuation of this groove makes a passage-way for the spring 136 (Figs. 7 and 8). Assuming that the clamp 127, 128 is open and in the position shown in Fig. 8, the free ends of the bill and carbon sheets may be introduced between the clamp and the platen face, and then the handle is pulled forward, giving a continuous rotation to the platen sufficient to rotate it in the present instance through approximately six revolutions so as to wind six plies of the paper with the interleaved carbon around the platen. During this continuous rotation the line space detent will be out of operation as will also the paper feeding rolls 172, and these parts will be restored to operative position only at the end of the platen rotating movement. As has been explained, the platen when arrested will present the outer bill sheet in position to have the first line thereon written. As is well understood the writing will take place through the actuation of the usual printing instrumentalities and ribbon mechanism of the standard Remington machine not herein disclosed but of regular construction. As the first line is written the carriage will, with the parts mounted thereon, space leftward step-by-step under the control of the usual escapement devices not herein shown; and when the end of the line is reached, the carriage will be restored from left to right and the platen line spaced, as has been explained, by actuation of the line space handle 69. The second and subsequent lines are thereafter written, the platen being line spaced in between, all as heretofore explained. It will be understood that each character written on the outer ply of the sheet through the ribbon will be duplicated on each of the five underlying bill forms or blanks through the carbon paper or transfer material 197. The writing of the bill having been completed, the carriage will be restored from left to right and the handle 101, when actuated, will turn the platen forward continuously to eject the bill. This ejection will be assisted by the pressure rolls 172. At the same time that the platen is operating to eject the bill, the carbon roll holder will be positively turned to rewind the carbon paper thereon, the spring connection comprising the spring 238 being effective to take up any slack due to the variation in the diameters 139

of the platen and the roll holder, just as such spring connection operated in the winding-on operation to yield to prevent the tearing or rending of the carbon paper. As the bill sheet 5 is retracted, it will be received in the receiving guide or paper holder comprising the parts 288 and 305 in folded form. As has been described the platen clamp opens automatically to release the written bill sheet 10 which may then be removed, the outward releasing action of the clamp also operating to throw off the pressure rolls 172 and lock them in inoperative position.

The operation above outlined may be 15 repeated with each bill sheet. It will be understood that in writing a bill, the tabulating mechanism and other devices associated with the Remington typewriting machine may be employed at convenience.

20 In practice it would be difficult to insure that the lower free end of the carbon paper should be so adjusted that it would always enter the opening between the clamping jaw 128 and the platen when the clamp is open as 25 in Fig. 8. It will be borne in mind, however, that the carbon paper is positively advanced by the driving mechanism, and hence its free end will almost immediately be confined or clamped, so to speak, between the platen 30 surface and that portion of the work sheet itself which lies just behind the clamped or positively held end of said sheet. It is, in fact, immaterial whether or not the carbon paper itself has its end caught beneath the 35 clamping jaw 128, since it will be bound to the platen by the overlying work sheet.

The toothed wheel 202 and the cooperating toothed member 230, 231 afford means for advancing a fresh portion of carbon from the 40 supply roll equal to a fractional line space extent so that the carbon may be written on between the lines first exhausted, thereby promoting even and complete exhaustion of the carbon sheet.

45 My divisional application Serial #285,884 contains claims directed to the following features disclosed herein:

Combinations including the carbon roll holder.

50 The carbon roll mechanism and its mounting etc.

The guide plate and feed rollers for the carbon sheet etc.

55 My divisional application Serial #293,435 contains claims directed to the following features disclosed herein:

Combinations including the magazine.

Means for preventing an operation of the platen rotating means except when the guide 60 on the carriage is in register with the magazine.

Means for preventing a rotation of the platen in the event that a work sheet is not properly positioned in the machine.

65 Work sheet guiding and directing means

on the carriage for guiding and folding the work sheets etc.

Changes of construction may be made without departing from my invention, and various features of it may be separately employed.

What I claim as new and desire to secure by Letters Patent, is:—

1. The combination of a rotary platen, a paper clamp mounted thereon, arms pivoted on the platen and pivotally connected with said clamp, spring means normally maintaining the clamp in clamping relationship with the platen, and automatically operating means for overcoming the force exerted by said spring means at a predetermined point in the rotation of the platen, said overcoming means including means for affording a plurality of complete rotations of the platen before becoming effective.

2. The combination of a rotary platen, a paper clamp, and controlling means for automatically actuating said clamp as the platen is rotated, said controlling means including means by which the controlling means are brought into use only after a plurality of complete revolutions of the platen.

3. The combination of a rotary platen, a spring-pressed paper clamp mounted thereon, automatic means for opening the clamp in opposition to the spring pressure, and means for maintaining said automatic means in ineffective position until the platen reaches a predetermined point after a revolution thereof in excess of one complete turn.

4. The combination of a rotary platen, a spring-pressed paper clamp mounted thereon, automatic means for opening the clamp in opposition to the spring pressure, and means for maintaining said automatic means in ineffective position until after a predetermined point has been reached, said maintaining means being adjustable so as to afford a variable number of uninterrupted revolutions of the platen before said automatic means can become effective.

5. The combination of a rotary platen, a paper clamp thereon and normally in cooperation with the platen, devices for arresting the rotation of the platen, other devices associated therewith for opening said clamp, both being normally out of use or ineffective, and automatically operating means for throwing said devices into use or for rendering them effective.

6. The combination of a rotary platen, a paper clamp thereon and normally in cooperation with the platen, devices for arresting the rotation of the platen, other devices associated therewith for opening said clamp, and automatically operating means including a cam member for throwing said devices into use at a predetermined point in the revolution of the platen.

7. The combination of a rotary platen, a

- paper clamp thereon and normally in cooperation with the platen, devices for arresting the platen, other devices associated therewith for opening said clamp, means including a cam member for throwing said devices into use, platen rotating means for turning the platen continuously, and a device operative by said rotating means to actuate said cam member.
8. The combination of a rotary platen, a paper clamp thereon and normally in cooperation with the platen, devices for arresting the platen, other devices associated therewith for opening said clamp, means including a cam member for throwing said devices into use, platen rotating means for turning the platen continuously, and a device operative by said rotating means to actuate said cam member at the end of a predetermined plurality of revolutions of the platen.
9. The combination of a rotary platen, a paper clamp thereon, devices for arresting the platen at a predetermined point in its rotation, devices associated with said arresting devices for opening said clamp, said arresting devices becoming effective only after a predetermined number of complete revolutions of said platen, and means for continuously turning the platen through said plurality of revolutions.
10. The combination of a rotary platen, a paper clamp thereon, devices for arresting the platen at a predetermined point in its rotation, devices associated with said arresting devices for opening said clamp, said arresting devices becoming effective only after a predetermined number of complete revolutions of said platen, and means for continuously turning the platen through said plurality of revolutions, said arresting devices including a cam member, and also a part cooperating with said cam member and rotated by said platen turning means.
11. The combination of a rotary platen; a paper clamp thereon; devices for arresting the platen at a predetermined point, comprising a cam member and a part cooperating therewith; devices associated with said arresting devices for opening said clamp; and means for continuously turning the platen through a plurality of revolutions, said part cooperating with said cam member at the end of the plurality of revolutions to arrest the platen and to open the clamp.
12. The combination of a rotary platen; a paper clamp thereon; devices for arresting the platen at a predetermined point comprising a cam member; devices associated with said arresting devices for opening said clamp; means for continuously turning the platen through a plurality of revolutions; a part controlled by the platen-turning means and cooperative with said cam member at the end of the predetermined revolutions to arrest the platen and to open the clamp; and a latch to hold the platen against rotary movement after its arrest.
13. The combination of a rotary platen, a paper clamp thereon, devices for arresting the platen at a predetermined point, comprising a cam member and a part cooperating therewith; devices associated with said arresting devices for opening said clamp; means for continuously turning the platen through a plurality of revolutions; said part cooperating with said cam member at the end of the predetermined revolutions to arrest the platen and to open the clamp; and a latch to hold the platen after its arrest, said latch being mounted on said cam member and cooperating with a pin on the platen.
14. The combination of a rotary platen, a paper clamp mounted thereon, means for opening the clamp automatically, and means for holding against rotation the platen while the clamp is open, said last mentioned means comprising a stop on the platen and relatively movable jaws cooperative simultaneously with opposite sides of said stop.
15. The combination of a rotary platen, a paper clamp normally cooperatively engaged therewith, means for automatically opening said clamp during rotation of said platen in one direction, and means for preventing rotation of the platen in the opposite direction until the clamp is closed.
16. The combination of a rotary platen, a paper clamp adapted to cooperate therewith, means for continuously rotating the platen including a finger piece, means for automatically opening and closing the clamp when the finger piece is actuated in opposite directions, and means for preventing rotation of the platen in either direction by the finger piece when the clamp is open.
17. The combination of a rotary platen, a paper clamp thereon, means for automatically opening the clamp during the rotation of the platen in one direction, stops for thereafter preventing further rotation of the platen, and a latch dropping into use automatically to prevent rotation of the platen in the opposite direction.
18. The combination of a rotary platen, a paper clamp thereon, means for automatically opening the clamp during the rotation of the platen in one direction, stops for thereafter preventing further rotation of the platen, a latch dropping into use automatically to prevent rotation of the platen in the opposite direction, and means for automatically unlatching said latch.
19. The combination of a rotary platen, a paper clamp thereon, means for automatically opening the clamp during the rotation of the platen in one direction, stops for thereafter preventing further rotation of the platen, an automatic latch, and spring means for closing the clamp while the latch remains

effective to prevent rotation of the platen in the opposite direction.

20. The combination of a rotary platen, a paper clamp thereon, devices for opening the clamp at a predetermined point in its rotation, other devices associated therewith for arresting the platen and comprising a cam member, means for rotating the platen continuously through a predetermined number of revolutions, an actuating roll on said rotating means coacting with said cam member to actuate said sets of devices, and a latch mounted on said cam member and coacting with the platen to prevent rotation thereof in the opposite direction as long as the clamp remains open.

21. The combination of a rotary platen, a paper clamp thereon, devices for opening the clamp at a predetermined point in its rotation, other devices associated therewith for arresting the platen and comprising a cam member, means for rotating the platen continuously through a predetermined number of revolutions, an actuating roll on said rotating means coacting with said cam member to actuate said sets of devices, a latch mounted on said cam member and coacting with the platen to prevent rotation thereof in the opposite direction as long as the clamp remains open, and means operative by said roll and said cam member to unlatch said latch.

22. The combination of a rotary platen, a paper clamp thereon, devices for opening the clamp and arresting the platen at a predetermined point in its rotation, means for holding the platen against rotation while the clamp is open, means for continuously turning the platen comprising a handle and a gear train between the handle and the platen, and a lost motion connection between said handle and said gear train whereby the handle is operative to close the clamp before the platen is released.

23. The combination of a rotary platen, a paper clamp thereon, devices for opening the clamp and arresting the platen at a predetermined point in its rotation, means for holding the platen against rotation while the clamp is open, means for continuously turning the platen comprising a handle and a gear train between the handle and the platen, and a lost motion connection between the said handle and said gear train, said lost motion connection comprising a split collar connected rigidly to the handle and provided with separated stops and a stop on said gearing interposed between said separated stops.

24. The combination of a platen, a paper clamp normally engaged with the platen, means for continuously rotating the platen including a handle and a lost motion connection between said handle and the platen, means for opening said clamp during the rotation of the platen, means for preventing movement of the platen while the clamp is

open, and means operated by said handle for throwing said preventive means out of use while taking up said lost motion connection.

25. The combination of a platen, a paper clamp normally engaged with the platen, means for continuously rotating the platen including a handle and a lost motion connection between said handle and the platen, said lost motion connection comprising a stop rigid with the handle and a pair of stops rigid with the platen and between which said first named stop is adapted to play, means for opening said clamp automatically, means for preventing movement of the platen while the clamp is open, and means operated by said handle for throwing said preventive means out of use while taking up said lost motion connection.

26. The combination of a rotary platen, a paper clamp thereon, means for opening and closing said clamp, feed rollers constantly spring pressed towards the platen, said clamp operating when opened to move said feed rollers to inoperative position, and locking devices to hold said feed rollers in inoperative position.

27. The combination of a rotary platen, a paper clamp mounted thereon, means for actuating said clamp, and paper feed devices mounted independently of the platen, said clamp operating to move said paper feed devices relatively to the platen to an ineffective or inoperative position.

28. The combination of a rotary platen, a paper clamp mounted thereon, and paper feed devices mounted independently of the platen, and means for automatically moving said clamp to inoperative position during rotation of the platen, said clamp when thrown out of use coacting with said paper feeding devices to throw them out of use.

29. The combination of a carriage, a platen thereon, a paper clamp on said platen, means operating automatically to throw said paper clamp away from the platen when it is turned, and paper feeding devices mounted on said carriage and thrown out of use by direct action of said paper clamp thereon.

30. The combination of a carriage, a platen thereon, a paper clamp on said platen, means operating automatically to throw said paper clamp away from the platen when it is turned, and paper feeding devices mounted on said carriage and comprising a spring pressed rock shaft, crank arms on said rock shaft, a feed roll shaft on said crank arms, and feed rolls on said shaft adapted to coact with the platen surface, said clamp when thrown out of use moving said rolls to inoperative position.

31. The combination of a carriage, a platen thereon, a paper clamp on said platen, means operating automatically to move said paper clamp away from the platen surface when the platen is turned, paper feeding devices

mounted on said carriage and comprising a spring pressed rock shaft, crank arms on said rock shaft, a feed roll shaft on said crank arms, and feed rolls on said shaft adapted to coat with the platen surface, said clamp when thrown out of use moving said rolls to inoperative position, and locking devices for holding said rolls in inoperative position.

32. The combination of a carriage, a platen thereon, a paper clamp on said platen, means operating automatically to move said paper clamp away from the platen surface when the platen is turned, a spring pressed rock shaft, crank arms on said rock shaft, a feed roll shaft on said crank arms, feed rolls on said shaft adapted to coat with the platen surface, said clamp when thrown out of use moving said rolls to inoperative position, projections on said crank arms, and spring pressed locking arms cooperative with said projections when the feed rolls are thrown off by the clamp.

33. The combination of a rotary platen, a paper clamp thereon, means for opening and closing said clamp, feed rolls constantly spring pressed towards the platen, a support for the feed rolls, said clamp operating when opened to move said feed rolls to inoperative position, and locking devices to hold said feed rolls in inoperative position, said locking devices comprising a spring pressed rock shaft, hooks thereon, and co-operating projections on the feed roll support.

34. The combination of a rotary platen, a paper clamp thereon, means for opening and closing said clamp, feed rolls spring pressed towards the platen, said clamp operating when opened to move said feed rolls to inoperative position, locking devices to hold said feed rolls in inoperative position, said locking devices comprising a spring pressed rock shaft, hooks thereon, cooperating projections on the feed roll support, means for continuously rotating the platen, an actuating pin on said platen rotating means, and a finger on one of said locking hooks engageable by said pin to throw the locking hooks off said projections and out of use.

35. The combination of a platen, means for rotating said platen, a paper feed device spring pressed towards the platen, and means for holding said paper feed device out of use, and said platen rotating means being effective at a predetermined point to release said paper feed device for cooperation with the platen.

36. The combination of a platen, means for rotating said platen, a paper feed device spring pressed towards the platen, a paper clamp on the platen effective when opened to move said paper feed device to inoperative position, locking means for holding said paper feed device in inoperative position, said platen rotating means being automatic-

ally effective to release said paper feed devices for cooperation with the platen.

37. The combination of a platen, a paper clamp, and paper feed devices positively connected to the platen, said clamp being adapted to break the positive connection between said platen and said paper feed devices.

38. The combination of a platen, means for turning the platen, paper feed devices, means for positively turning the paper feed devices when the platen is turned, and means for automatically rendering inoperative said positive turning means for the paper feed devices.

39. The combination of a platen, means for turning the platen, paper feed devices, means for positively turning the paper feed devices when the platen is turned, and means for automatically rendering inoperative said positive turning means operating at a predetermined point in the rotation of the platen.

40. The combination of a rotary platen, means for turning the platen, rotary paper feed devices, means for positively turning the paper feed devices when the platen is turned, means for automatically rendering inoperative said positive turning means, and other means for causing said positive means again to become effective.

41. The combination of a platen, means for turning the platen, rotary paper feed devices, means for positively turning the paper feed devices from the platen, means for automatically rendering inoperative said positive turning means and the paper feed devices, said last recited means operating at a predetermined point in the rotation of the platen, and other means operating at a predetermined point in the rotation of the platen in the reverse direction to again cause said positive means to become effective.

42. The combination of a platen, a paper clamp thereon, means for opening said clamp, paper feed devices, and positive connections between said paper feed devices and said platen, the means for opening the clamp operating automatically to break said positive connections.

43. The combination of a platen, a paper clamp thereon, means operating automatically to open said clamp, a feed roll cooperative with said platen, and positive connections between said feed roll and said platen comprising a gear wheel on the platen axle and an intermeshing pinion on the feed roll shaft, the means for opening the clamp operating automatically to separate said pinion and said gear wheel.

44. The combination of a platen, means for rotating said platen, paper feed rollers adapted to coat with the platen, and means controlled by said platen rotating means for automatically controlling the movements of

the feed rollers into and out of contact with the platen.

45. The combination of a platen, means for rotating said platen, paper feed rollers shiftable into and out of cooperative relation with the platen, and means controlled by said platen rotating means for automatically moving said feed rollers away from the platen and while the latter is in a given predetermined position of rotation.

46. The combination of a platen, means for rotating said platen, paper feed rollers shiftable into and out of cooperative relation with the platen, and means controlled by said platen rotating means for automatically effecting a movement of said feed rollers into cooperative relation with the platen.

47. The combination of a platen, means for rotating said platen, paper feed rollers shiftable into and out of cooperative relation with the platen, and means controlled by said platen rotating means for automatically effecting a movement of said feed rollers into cooperative relation with the platen after a predetermined plurality of revolutions of the platen has been effected.

48. The combination of a platen, means for rotating said platen, paper feed rollers shiftable into and out of cooperative relation with the platen, and means controlled by said platen rotating means for automatically moving said feed rollers away from the platen and for maintaining them thus cast-off until the platen has made a predetermined plurality of revolutions and for then effecting a movement of the feed rollers into cooperative relation with the platen.

49. The combination of a platen, means for rotating said platen forward and backward, paper feed rollers shiftable into and out of cooperative relation with the platen, and means controlled by said platen rotating means for automatically shifting said feed rollers out of cooperation with the platen and for maintaining them thus shifted during a predetermined plurality of backward rotations of the platen and for automatically effecting a shifting of said feed rollers into cooperation with the platen at about the termination of said backward rotation of the platen.

50. The combination of a platen, means for guiding a work sheet from above to the front of the platen, means for limiting the extents of forward and backward rotations of the platen, means for turning the platen forward and backward, a work sheet clamp carried by the platen, and automatically operating means for closing said clamp preliminary to a backward rotation of the platen from the limit of its forward movement and for automatically opening said clamp at about the limit of the backward rotation of the platen.

51. The combination of a platen, a work sheet clamp carried thereby, means for turn-

ing said platen, means for locking said platen against turning movement, and automatically operating means for effecting a closing of said clamp as a preliminary to moving said platen and while the latter is at rest and for then releasing said platen locking means and rotating the platen.

52. The combination of a rotative platen, a paper clamp carried thereby, platen rotating means, and automatically operating controlling means for said clamp brought into action to shift the clamp after a plurality of revolutions of the platen.

53. The combination of a rotative platen, a paper clamp carried thereby, means for rotating the platen forward and backward, and automatically operating means for opening said clamp at or about the completion of a plurality of backward revolutions of the platen.

54. The combination of a rotative platen, a paper clamp carried thereby, means for rotating the platen forward and backward, automatically operating means for opening said clamp at or about the completion of a plurality of backward revolutions of the platen, and adjustable means for predetermining the number of the plurality of backward revolutions the platen shall receive before the clamp is opened.

55. The combination of a rotative platen, a clamp carried by the platen, means for turning said platen forward and backward, means for arresting the platen in its forward and backward movements after a plurality of revolutions, automatically operating means for closing the clamp preliminary to turning the platen backward and for opening the clamp at the termination of its backward movement through a plurality of revolutions.

56. The combination of a platen, a paper clamp for clamping paper to the platen, means for actuating said clamp, and paper feed devices cooperative with the platen, the construction and relation of the parts being such that said clamp when actuated also actuates said paper feed devices to release them from the platen.

57. The combination of a platen, a paper clamp carried thereby, means for controlling the movement of said clamp into and out of use or clamping position, and paper feed devices, said clamp when thrown out of use coating with and also throwing said paper feed devices out of use.

Signed at the borough of Manhattan, city of New York, in the county of New York and State of New York this 12th day of April, A. D. 1927.

EDWIN E. BARNEY.
